US00D908364S

(12) **United States Design Patent** (10) Patent No.: **US D908,364 S**
(45) Date of Patent: ** Jan. 26, 2021

(54) **HEAD FOR DENTAL APPLIANCE**

(71) Applicant: **Dyson Technology Limited**, Wiltshire (GB)

(72) Inventors: **Stephen Benjamin Courtney**, Bath (GB); **Timothy Nicholas Stickney**, Gloucester (GB); **Thomas James Dunning Follows**, Swindon (GB); **William John Bex-Russell**, London (GB)

(73) Assignee: **Dyson Technology Limited**, Malmesbury (GB)

(**) Term: **15 Years**

(21) Appl. No.: **29/682,800**

(22) Filed: **Mar. 7, 2019**

Related U.S. Application Data

(62) Division of application No. 29/602,341, filed on May 1, 2017, now Pat. No. Des. 847,513.

(57) **CLAIM**

We claim the ornamental design for a head for dental appliance, as shown and described.

DESCRIPTION

FIG. 1 is a perspective view of a head for dental appliance showing our new design;

FIG. 2 is a front view thereof;

FIG. 3 is a rear view thereof;

FIG. 4 is a side view thereof;

FIG. 5 is a side view of the opposite side of FIG. 4;

FIG. 6 is a top view thereof; and,

FIG. 7 is a bottom view thereof.

The broken lines shown in the drawings illustrate portions of a head for dental appliance that form no part of the claimed design.

1 Claim, 7 Drawing Sheets
